CORPORATION OF CONNECTICUT

CANDLE FLASH LIGHT

Application filed April 2, 1931. Serial No. 527,130.

This invention relates to new and useful improvements in portable electric lights of the kind adapted to be carried in the hand.

An object of the invention is to provide a portable electric light generally in the form of a candle and including a glass at its upper end disposed over a light bulb the glass being adapted to be removed from the light to expose the bulb without removing or disassembling any other parts of the device.

Another object is to provide a portable electric light generally in the form of a candle and including switch means whereby when the light is placed on a support the light bulb is extinguished and whereby when the light is raised off the support the bulb is energized and including other switch means adapted to be closed and remain closed to energize the bulb.

A further object is to provide a portable electric light generally in the form of a candle and including a battery and a bulb and switch means whereby when the light is placed on a support the circuit through the bulb and battery is open and when the light is raised off the support the circuit through the bulb and battery is closed and including means whereby this switch means may be rendered inoperative.

An additional object is to provide a portable electric light generally in the form of a candle and including a battery and a bulb and switch means whereby when the light is on a support the circuit through the bulb and battery is open and when the light is raised off the support the circuit through the bulb and battery is closed, said switch means being so constructed that it may be rendered entirely inoperative, and the device including other switch means adapted to be manually opened and closed.

Yet another object is to provide a portable electric light generally in the form of a candle and including a sheet metal casing and sheet metal base adapted to be easily assembled whereby the light may be manufactured at low cost and is light in weight.

Other and additional objects and advantages will become apparent from a consideration of the following detailed description

taken in connection with the accompanying drawing wherein a satisfactory embodiment of the invention is shown. However, it will be understood that the invention is not limited to the details shown and described but includes all such variations and modifications as fall within the spirit of the invention and the scope of the appended claims to which claims reference is to be had for a definition of the invention.

In the drawing:

Fig. 1 is a side elevational view of the complete light;

Fig. 2 is a view partly in side elevation and partly in section and on an enlarged scale;

Fig. 3 is a sectional view on the line 3—3 of Fig. 2;

Fig. 4 is a top plan view of the upper end of the casing with the glass and bulb removed;

Fig. 5 is a bottom plan view of the light, portions of the base being broken away;

Fig. 6 is a detail sectional view substantially on the line 6 of Fig. 2; and

Fig. 7 is a view somewhat similar to Fig. 6 but showing the switch bar in the act of being turned to render the automatic switch inoperative.

Referring in detail to the drawing, the improved light includes a base 10 supporting a casing 11 within which is disposed a battery 12 and at the upper end of which is arranged a bulb 13 adapted to be enclosed by a glass dome 14 removably mounted on the upper end of the casing as will later be described in detail.

The base 10 is formed of sheet metal and may be of any desired shape. That shown is shaped to provide steps at 15 and 16 and may have its outer edge turned to provide the supporting bead 17 adapted to rest on a table or the like without marring the same. Centrally of its upper surface or step 16 the base includes an inturned portion 18 pressed to provide screw threads as clearly shown in Fig. 2 and from the lower end of the screw threaded portion 18 the material of the base is carried inwardly to provide an annular ledge or flange 19.

Supported by the ledge or flange 19 and se-

cured to the under side thereof as by rivets 20 and 21 is a disc of insulating material 22. These rivets are of course in electrical contact with the flange 19. A block 23 of wood 5 or other non-conducting material is secured to the upper side of the disc 22 centrally thereof and as shown projects a considerable distance above the base 10. To the upper end or side of the block 23 there is secured 10 a spring contact member 24 including a mounting portion 25 and an overhanging spring contact portion 26. Preferably the contact member 24 is secured to the block 23 and both parts secured to the disk 22 by 15 means of a relatively long rivet 27. This rivet is in electrical engagement with the contact member 24 and its head 27' is exposed at the underside of disc 22.

A bracket 28 having a rectangular opening 29 therethrough is carried by the block 23 at one side thereof as shown in Fig. 2. Operating through this bracket and through the rivet 21 is a rod 30 at its upper end carrying a contact finger 31 adapted to engage the 25 contact element 24 as suggested by the dotted lines in Fig. 2, when the rod 30 is in its lowermost position. The rod 30 is mounted for vertical movement through the bracket and rivet, and the upper portion of the rod is 30 rectangular or other shape in cross section to conform to the configuration of the opening 29 in the bracket 28 whereby the rod is not free to rotate in the bracket.

The lower end portions 32 of the rod may 35 be circular in cross section to conform to the opening through the rivet 21. At the lower side of the disc 22 a spring 33 is disposed about the rod 30 between the head 34 of the rod and the rivet 21. Obviously, the spring 40 normally tends to expand and move the rod downwardly or outwardly with respect to the casing 11. When the light is on a table or other support as suggested at 35 the spring 33 is held against operation and finger 31 is raised from and held out of contact with the contact 24, but as soon as the light is elevated off the support the spring will act to slide the rod and bring the finger 31 into contact with the contact element 24. 50 This action will result in the energizing of the bulb 13 as will be set forth.

The central terminal 36 of the battery 12 is normally in engagement with the central contact of the bulb 13 as shown in Fig. 2. 55 The battery is held in this position by means of the spring contact member 24 which has its resilient portion 26 disposed against the underside of the battery and in contact with the casing thereof and normally functioning to support the battery with its terminal 36 in engagement with the central contact of the bulb. Since the bulb is grounded on the casing and since the rod is in contact with the casing through the flange 19 and screw 60 threaded engagement of the lower end por-

tion of the casing with the portion 18 of the base, movement of the rod to bring its finger 31 into engagement with the contact element 24 will close the circuit through the battery and bulb whereby the latter will be energized. 70

The casing 11 is detachably secured to the base 10 by threading the lower end portion of the casing into the threaded portion 18 of the base. Thus, the parts are secured together whereby the base may support the casing in vertical position and yet the parts may be easily disconnected to permit access to the interior as for replacement of the battery or the repair of a switch element. At 75 its upper end the casing 11 has an integral inwardly turned portion 37 including a slightly raised portion having a curved flange 38 through which the stem of the bulb is threaded whereby the bulb is grounded on 80 the casing and supported by the casing. This flange may have a notch 38' at one side to permit entrance of the thread on the bulb.

As before stated the glass dome 14 is removable mounted on the member of the casing and according to the present invention the glass is so mounted as to be removable from the casing without disassembling any other parts or the like. Therefore, should the bulb 13 be burnt out access may be had 90 to the bulb to replace the same simply by removing the glass 14 and the new bulb may be threaded through the portion 38 until the inner end of the stem engages the central terminal of the battery after which the glass 95 may be replaced on the casing.

For cheapness in manufacture it is preferable to form the securing means for the glass 14 separate from the casing and to thereafter secure the means to the casing. As herein disclosed the securing means includes a flat ring 39 formed of sheet metal and at spaced points about its outer edge carrying upturned spring fingers 40 adapted to snap about a ring or bead 41 at the lower open end of the glass 14 whereby to removably secure the glass. At their upper end portions the fingers 40 are turned outwardly as at 42 whereby the glass may be applied or mounted by pressing it downwardly between the fingers. 110

The inturned wall 37 at the outer end of the casing is provided with spaced perforations and the flat ring 39 is preferably lanced at 115 spaced points and then has lugs 43 pressed downwardly therefrom. These lugs may be passed through the openings in the wall 37 of the casing and doubled upon themselves as best shown in Fig. 2 whereby to rigidly 120 secure the ring in place on the casing. Since the portion 38 of the casing extends upwardly through the ring such portion will assist in positioning the ring on the casing so as to bring the lugs 43 on the ring into alignment. 125

ment with the perforations in the wall 37 of the casing.

Pivottally mounted at the underside of disc 22 by the rivet 20 is a manually operable switch member 44 including a contact portion 45 and a hand or finger piece 46. The member 44 extends through a slot 47 in the base whereby the finger piece 46 is disposed at the outer side of the base and in position 10 to be grasped to rock the member on its pivot 20 to either open or close a circuit through the battery 12 and bulb 13.

When member 44 is rocked on its pivot to bring its portion 45 into engagement with the 15 lower end of the rivet 27 a circuit is closed between the battery and bulb and the bulb is energized. The complete circuit may be described as through the contact member 24, rivet 27, switch member 44, rivet 20, flange 20 19 and casing 11 through its screw threaded connection with the base, bulb 13 and through the central contact of the bulb to the central contact 36 of the battery.

From the description thus far it will be 25 seen that when the light is deposited on a support as for example the table 35, rod 30 is moved upwardly against the action of spring 33 whereby to carry its finger 31 out of engagement with the contact member 24. 30 Therefore, the circuit through this switch mechanism is open. Should it be desired to close the circuit to energize the bulb 13 while the light is on a support it is but necessary to operate the switch member 44 by moving 35 it about its pivot to bring its contact portion 45 into engagement with the lower end of the rivet 27. The switch member will stay in this position until moved therefrom and the circuit through the bulb and battery will 40 accordingly remain closed irrespective of the position of the light. It is to be noted the handle 46 is exposed at the top of the base so the switch may be operated without lifting the device from the table or other support.

Means are provided whereby the switch mechanism including the rod 30 may be decommissioned. At a point normally below the bracket 28 the rod 30 is notched as at 48. 50 For the greater portion of its length the rod fits snugly through the opening 29 in the bracket 28 and is not free to turn in this opening. However, the notched portion 48 of the rod is of such reduced cross sectional area 55 that by grasping the head 34 on the rod and pressing the rod inwardly or upwardly to bring this notch into the opening 29 in the bracket 28 the rod may be rotated to dispose its contact finger 31 in an inoperative position as suggested by the dotted lines in Fig. 3. Fig. 7 shows the rod 30 in the act of being turned and with its notched portion 48 located in the opening 29 of the bracket 28. With the rod turned as suggested it is obvious that the finger 31 will not engage the

contact member 24 to close a circuit when the spring 33 acts to move the rod downwardly or outwardly.

With the one switch mechanism decommissioned as explained in the foregoing paragraph, it will be seen that the light will not be automatic in its operation and that it may be handled without the bulb 13 being energized and that the circuit to the bulb may be opened or closed at will by manual manipulation of the switch member 44.

It is desired to point out that should the battery 12 need replacing it is but necessary to separate the base and casing as by unscrewing them and that the battery may then be readily removed and replaced. Further, it will be seen that on separation of the base and casing the switch elements which are all carried by the base are exposed for observation and repair or adjustment. Thus it will be seen that the battery may be replaced without disturbing the bulb and as has been previously explained the bulb may be replaced without disturbing the position of the battery or disconnecting the base and casing.

The base, casing and means for securing the glass to the casing are all of sheet metal and may therefore be constructed at low cost and it will also be noted that the single disc 22 of insulating material carried by the base supports the two switch means and additionally supports the spring contact member which not only serves as a contact but also serves to hold the battery in engagement with the bulb. It should also be noted that the switch members are mounted by the same rivets which secure the disc 22 to the annular flange 19 on the base and that these rivets further serve as connections in the respective circuits.

Having thus set forth the nature of our invention, what we claim is:

1. In a portable electric light generally in the form of a candle, a base of sheet metal, a casing of sheet metal threaded to said base, a bulb at the upper end of said casing, a battery in said casing, a disc of insulating material carried by the base, a post of insulating material carried by the disc, a spring contact carried by the post and engaging the lower end of the battery and acting to maintain the battery in engagement with the bulb, and switch means carried by the disc and operable to close a circuit between the battery and bulb.

2. In a portable electric light generally in the form of a candle, a casing adapted to receive a battery, a base adapted to support said casing in a vertical position, said base and casing detachably secured together, means mounting a bulb at the upper end of the casing, means removably mounting a glass over said bulb, a battery in said casing, switch means for closing a circuit through the battery and bulb, means mount-

ing the switch means on the base, said switch means including a vertically reciprocatable rod, means normally serving to hold said rod against turning movement, and means whereby said rod may be manually adjusted relative to said means and turned about its own longitudinal axis to render the switch means inoperative.

3. In a portable electric light generally in the form of a candle, a casing adapted to receive a battery, a base adapted to support said casing in a vertical position, said base and casing detachably secured together, means mounting a bulb at the upper end of the casing, means removably mounting a glass over said bulb, a battery in said casing, automatic switch means adapted to close a circuit between the battery and bulb when the light is raised off a support and to open the circuit on the light being deposited on a support, said switch means including a vertically reciprocatable rod, means normally serving to hold said rod against turning movement, means whereby said rod may be manually adjusted relative to said means and turned to render the switch means inoperative, and other switch means adapted to be manually operated to closed and opened positions and to remain in adjusted position until manually moved therefrom.

4. In a portable electric light generally in the form of a candle, a casing adapted to receive a battery, a base adapted to support said casing in a vertical position, a wall at the upper end of said casing, said wall having a centrally raised and perforated portion, a bulb having its stem arranged in the perforation in said centrally raised portion, a ring secured to said wall at the base of said raised portion and centered by said portion, spring clips carried by said ring and extending upwardly therefrom in spaced relation to the raised portion of the wall, a glass disposed over said bulb, said glass having a bead adapted to be engaged by said spring clips whereby to removably secure the glass in place, a battery in said casing, and means to close a circuit through the battery and bulb.

5. In a portable electric light generally in the form of a candle, a base, a casing removably mounted on the base, said casing open at its lower end, a bulb at the upper end of the casing, a battery in the casing, a disc of insulating material carried by the base and closing the lower end of the casing when the casing is mounted on the base, a post of insulating material carried by the disc, a contact carried at the upper end of the post and engaging the lower end of the battery, a pair of rivets securing the disc to the base and extending through the disc and base, one of the rivets of said pair being hollow, a switch means slidably operating through the hollow rivet and adapted when

the light is raised off a support to engage the contact and close a circuit between the battery and bulb and when the light is deposited on a support to be moved away from the contact to open the circuit, said hollow rivet forming part of said circuit, a rivet securing the contact to the post and extending through the base, and a manually operable switch means pivoted on the second of said pair of rivets and operable to engage the rivet through the post to close a circuit through the battery and bulb independent of the first switch means.

6. In a portable electric light generally in the form of a candle, a base, a casing removably mounted on the base, said casing open at its lower end, a bulb at the upper end of the casing, a battery in the casing, a disc of insulating material carried by the base and closing the lower end of the casing when the casing is mounted on the base, a post of insulating material carried by the disc, a contact carried at the upper end of the post and engaging the lower end of the battery, a pair of rivets securing the disc to the base and extending through the disc and base, one of said rivets being hollow, a switch means slidably operating through the hollow rivet and adapted when the light is raised off a support to engage the contact and close a circuit between the battery and bulb and when the light is deposited on a support to be moved away from the contact to open the circuit, and said hollow rivet forming part of said circuit.

7. In a portable electric light generally in the form of a candle, a casing adapted to receive a battery, a base supporting said casing in vertical position, said base and casing detachably secured together, means mounting a bulb at the upper end of a casing, a battery in the casing, switch means for closing a circuit through the battery and bulb and normally automatically operable to close a circuit between the battery and bulb when the light is raised off a support and to open the circuit on the light being deposited on a support, said switch means including a stationary contact, a vertically reciprocatable rod laterally of said contact, a contact arm on said rod and extending laterally therefrom to engage said stationary contact when the light is raised off a support, means normally serving to hold said rod against turning movement, and means whereby said rod may be manually adjusted relative to said means and then turned to carry its contact arm into a position extending away from said stationary contact whereby to render said switch inoperative.

8. In a light, a casing, a base at one end of said casing, a bulb upon said casing, a source of electrical energy, a switch comprising a stationary contact member, a movable contact member, means normally urging said movable contact into engagement with the

stationary contact, a longitudinally movable pin for actuating said movable contact member, a plate secured to said base, and cooperating means upon said pin and plate for holding said pin in position with said contact members out of engagement.

9. In a light, a casing, a base for said casing, a bulb upon said casing, a source of electrical energy, a switch comprising a stationary contact member, a movable contact member and a longitudinally movable pin for actuating said movable contact member, a support upon said base for insulatingly carrying said stationary contact member, cooperating means upon said base and pin comprising a member fixed to said pin for holding said pin in position with said contact members out of engagement, and yieldable means between said support and last mentioned member for normally urging said pin in a direction to bring said contact members into engagement.

10. In a light, a casing, a base at one end of the casing, a bulb upon the casing, a source of electrical energy, a switch comprising a stationary contact, a movable contact, means normally urging said movable contact into engagement with the stationary contact, an axially movable rotatable pin for actuating said movable contact member normally extending below the plane of the supporting surface of the base when the contacts are in the aforesaid engaged position, and means operable upon rotation of the pin to hold the same above the plane aforesaid of the base wherein the contacts are out of engagement.

In testimony whereof we affix our signatures.
